UNITED STATES PATENT OFFICE

2,439,628

BOTTLE STOPPER

Donald G. Kopecky, Taft, Calif.

Application February 2, 1945, Serial No. 575,787

1 Claim. (Cl. 215—54)

1

The present invention relates to new and useful improvements in stoppers designed particularly for use with "Thermos" bottles and similar types of containers, and the invention has for its primary object to provide an expandable body or plug portion of the stopper together with means operable outwardly thereof to expand the plug or body into tight hermetically sealing engagement with the internal surfaces of the neck of the bottle or container.

A further important object of the invention is to provide an expandable plug or body portion for the stopper having a flange on its outer end adapted to seat on the outer edge or lip of the neck of the bottle together with a rigid cap operable to compress the flange into tight sealing engagement with the lip of the bottle together with means for expanding the external walls of the plug or body into tight fitting engagement with the internal walls of the neck of the bottle.

A still further object is to provide a bottle stopper of this character of simple and practical construction, which is efficient and reliable in use, relatively inexpensive to manufacture, and otherwise well adapted for the purposes for which the same is intended.

Other objects and advantages reside in the details of construction and operation, as more fully hereinafter described and claimed, reference being had to the accompanying drawing forming part hereof, wherein like numerals refer to like parts throughout, and in which the figure represents a fragmentary sectional view through the neck of the bottle showing the stopper in position therein.

Referring now to the drawing in detail, wherein for the purposes of illustration I have disclosed a preferred embodiment of the invention, the numeral 5 designates the body portion of the stopper which may be made of resilient material like synthetic or natural rubber and which constitutes a plug adapted to fit within the neck 6 of a conventional form of "Thermos" bottle or other suitable container.

The outer end of the body portion 5 of the stopper projects outwardly beyond the neck 6 and is formed with an annular flange 7 overlying the outer edge or lip of the neck of the bottle, the flange being formed on its under surface with a groove 8 adapted to conformably receive the rounded edge of the lip of the bottle.

A vertical chamber or recess 9 is formed in the body 5 in which is positioned a rigid sleeve 10 which is internally threaded and formed with a flange 11 at its lower portion embedded in the

lower portion of the body 5. The flange 11 is embedded in the body 5 above the bottom portion of the body so that the flange and sleeve 10 are protected from contact with the contents of the bottle.

The screw 12 is threaded in the sleeve 10 and projects outwardly through the top of the body 5, the outer end of the screw having a manipulating head or knob 13 formed thereon.

10 The head or knob 13 is adapted to bear against a rigid cap 14 which is freely carried on the upper portion of the screw 12 and completely overlies the top of the body 5.

The under side of the cap 14 is formed with an 15 annular groove 15 adapted to conformably receive an annular rib 16 formed on the upper surface of the flange portion 7 of the body 5.

The under side of the cap 14 is also formed with an annular rib 17 projecting into the chamber 20 against the walls thereof, the rib 17 preventing lateral inward compressing movement of the upper portion of the body 5.

The central portion of the cap 14, at its under side, is formed with a recess 18 in which a metallic washer 19 is rotatably seated and the washer 19 is rigidly mounted on the smooth upper portion of the screw 12.

The cap 14 may be constructed of plastic or other suitable material and cemented or otherwise suitably secured to the top of the body 5.

The head 13 of the screw 12 may also be embedded in a plastic cover 20, the under side of the head of the screw being flush with the under side of the cover 20 to bear against the top of the cap 14 at the central portion thereof.

With the parts assembled in the position as illustrated in the drawing, and with the body or plug portion 5 of the stopper inserted in the neck 6 of the container, the screw 12 may then be manipulated to compress the plug or body 5 whereby to cause an expansion thereof and also produce a tight and hermetically sealing engagement between the surface of the plug and the inner walls of the neck of the container.

45 At the same time, the flange 7 of the plug or body portion 5 is compressed tightly downwardly against the upper edge or lip 8 of the container.

The purpose of having plug 5 cemented or otherwise secured to cap 14 as the final assembly 50 operation was included to give the assembled stopper the following advantage when in use.

When removing the stopper from the neck of the bottle the first step is to manipulate plastic cover 20 to decompress plug 5 laterally. When 55 plastic cover 20 has been manipulated to a certain

point, plug 5 becomes decompressed to its normal shape and size, this being only slightly smaller than the inside diameter of the neck of the bottle. However, by continuing to manipulate plastic cover 20 in a decompressing direction of rotation, plug 5 is caused to be stretched vertically, it being held down at its lower extremity by flange 11 and pulled upward at its upper extremity by cap 14, the cementing or securing of plug 5 to cap 14 binding them as a unit, washer 19 acting to raise cap 14 upon manipulation of plastic cover 20.

It is now evident that the lateral diameter of plug 5 is decreased in proportion with the increase of the vertical dimension of plug 5, thus giving both a positive and negative action to the plug 5. This action eliminates sticking or wedging of plug 5 in neck 6. It also makes one size stoppers adaptable to a wider range of bottle neck sizes. Further advantage is realized from the fact that after a certain period of use has elapsed the tendency of plug 5 to return to its natural size and shape is decreased. However, the compressing and retracting action of such a designed or constructed stopper naturally creates either of the above actions even though natural action on the part of plug 5 has been destroyed by continuous use, heat or other causes.

Another advantage directly related to the cementing of plug 5 to cap 14 is as follows:

Upon manipulating cover 20 in a direction tending to stretch plug 5, an effort to break the bond between cap 14 and plug 5 is created, however, this effort is controlled by the length of the threads in sleeve 10 and on screw 12. When cover 20 has been manipulated to a point where the bonding between plug 5 and cap 14 has reached a predetermined amount of tension, threads of sleeve 10 and screw 12 disengage making it impossible to break the bond or otherwise harm the stopper. The rounded, lower end of screw 12 maintains alignment with sleeve 10 and also is held in position for immediate re-engagement by compression created by plug 5 so that when cover 20 is manipulated, in a compressing direction with relation to plug 5, threads are re-engaged immediately.

It is believed that the details of construction

and operation, manner of operation and advantages of the device will be readily understood from the foregoing without further detailed explanation.

Having thus described the invention, what I claim is:

A bottle stopper comprising a plug made of resilient material adapted to enter the neck of a bottle, the outer end of said plug projecting outwardly beyond the neck of the bottle and being formed with an annular flange overlying the outer edge of the neck of the bottle, said flange being provided on its under surface with a groove adapted to conformably receive the outer edge of the neck of the bottle and on its upper surface with an annular rib, there being a vertical recess in said plug, an internally threaded and rigid sleeve provided with a flange at its lower end mounted in said vertical recess, the flange of the sleeve being imbedded within the plug above its bottom thereof, a rigid cap overlying the annular flange of said plug, said cap being provided on its underside with an annular groove adapted to conformably receive the annular rib on the flange of said plug and on its underside with an annular rib projecting into and bearing against the walls of said vertical recess, there being a recess in the central portion of said cap at its underside, a metal washer seated in the recess of said cap, and a screw extending through the recess and metal washer in said cap and threaded in said sleeve and operable upon manipulation in the proper direction to compress the flange of the plug against the neck of the bottle and to expand the plug within the neck.
